UNITED STATES PATENT OFFICE.

WALTER A. GOERTZ, OF EAST ORANGE, NEW JERSEY, ASSIGNOR TO AUGUST GOERTZ & CO., A CORPORATION OF NEW JERSEY.

DESIGN FOR A METALLIC CASE OR BOX.

Application filed July 10, 1926. Serial No. 18,296. Term of patent 3½ years.

To all whom it may concern:

Be it known that I, WALTER A. GOERTZ, a citizen of the United States, residing at East Orange, in the county of Essex and State of New Jersey, have invented a new, original, and ornamental Design for Metallic Cases or Boxes, of which the following is a specification, reference being had to the accompanying drawing, forming part thereof.

In said drawing, Figure 1 is a plan or face view of a metallic case or box, showing my new design; Figure 2 is a side edge elevation of the same; and Figure 3 is an end edge elevation of the same.

I claim:

The ornamental design for a metallic case or box, as shown.

WALTER A. GOERTZ.
